C. L. Luallen, INVENTOR
BY Victor J. Evans
ATTORNEY

Paul W. Hunt,

WITNESS:

UNITED STATES PATENT OFFICE.

CALVIN L. LUALLEN, OF COAL CREEK, TENNESSEE, ASSIGNOR OF TWO-THIRDS TO
HORACE M. MADDEN, OF COAL CREEK, TENNESSEE.

HORSESHOE.

Application filed May 24, 1921. Serial No. 472,160.

To all whom it may concern:

Be it known that I, CALVIN L. LUALLEN, a citizen of the United States, residing at Coal Creek, in the county of Anderson and State of Tennessee, have invented new and useful Improvements in Horseshoes, of which the following is a specification.

My present invention has reference to improvements in the construction of horse-shoes.

My object is to produce a horseshoe which shall be materially lighter in weight than the ordinary shoe but which is of such construction as to embody more strength, and consequently render the same susceptible to a greater period of wear than the ordinary horseshoe.

It is a further object to produce a horseshoe constructed of sheet metal, having its body, at its outer edge flanged downwardly to reinforce the said body, the flanges at the toe and heel portions providing calks, the toe calk being weightier than the heel calks, whereby the animal will have a tendency to first cause the toe portion of the shoe to engage with the ground surface, which, together with the weight of the animal will cause the toe calk to be embedded in the ground surface, and consequently prevent slipping and lateral or backward movement of the animal.

It is a still further object to produce a horseshoe constructed of sheet metal in which the outer edge is flanged to reinforce the body thereof, whereby a light, strong shoe is produced and which while adaptable for lightly shod animals, such as saddle or race horses, is equally adaptable for use on draft animals, and which, by virtue of the particular and peculiarly shaped calks provided by the flanges is especially adaptable for use on animals in mountainous countries.

It is a still further object to produce a horseshoe constructed of metal in which the outer edge thereof is provided with a continuous flange for reinforcing the body of the shoe, said flange being projected at the heel and toe portions of the shoe to provide the same with calks, and the said flange also providing concealing or protector means for the heads of the nails employed for securing the shoe on the hoof of the animal.

The foregoing, and other objects which will appear as the nature of the invention is better understood, may be accomplished by a

construction such as is disclosed by the drawings which accompany and which form part of this specification.

In the drawings:

Figure 1 is a perspective view looking toward the under face of a horseshoe in accordance with this invention.

Fig. 2 is a sectional view taken approximately on line 2—2 of Fig. 3,

Fig. 3 is a sectional view on the line 3—3 of Fig. 2,

Fig. 4 is a sectional view through the toe calk portion of the shoe,

Fig. 5 is a perspective view illustrating a slight modification, and

Fig. 6 is a view showing the toe calk before its respective portions are bent around and welded to the block.

My improved horseshoes are constructed in stock sizes so that the same will readily fit different sizes of hoofs of animals. The metal from which the shoes are constructed is, however, of a nature to render the same ductile under the hammer, so that the same may be placed upon an anvil in either a heated or cooled condition and properly shaped to fit irregular forms of animals' hoofs.

The shoe is broadly indicated by the numeral 1 and is constructed of sheet metal. The metal is comparatively thin, and the body 2 of the shoe is of a shape conformable to the ordinary horseshoe. The body 2 at its outer perimeter is provided with a continuous downturned flange 3, the said flange at the toe and heel portions thereof having extensions 4 and 5 respectively. The arcuate toe extension 4 provides the toe calk. The calk 4 is of a length approximately equaling the width of the shoe at the toe portion thereof, and embodies a materially greater amount of metal than the projecting heel portions and thus adds to the weight of the shoe at the toe portion. This is an important feature of the improvement, inasmuch as the weighted toe will have a tendency to cause the animal to bring the toe calk first in contact with the ground surface, and the added weight of the animal on the shoe will cause the calk to be embedded in the said ground surface. As a consequence, the animal will be prevented from slipping and from moving either laterally or backwardly. The result is that the shoe is particularly desirable for use.

on slippery surfaces and in mountainous regions.

The heel projections 5 have their outer ends bent inwardly, as at 6, and these projections 5 have further extending portions 7 which are bent inwardly against the end of the shoe and against the lateral or inwardly projecting portions 6, and these flanged portions provide the heel of the shoe with pockets that receive therein filler blocks 8. It is, of course, to be understood that the filler blocks are welded to the walls of the pockets, and it is to be also understood that the filler blocks do not sufficiently add to the weight of the heel portion of the shoe to counterbalance the weighted toe portion thereof. The body 2 inward of the side flanges 3 is provided with the usual openings 9 for the nails that enter the animal's hoof for securing the shoe thereon. The side flanges protect the heads of the nails, and the said heads, when brought into engagement with a ground surface, serve as additional calks, which is also true with respect to the side flanges 3.

In Fig. 5 of the drawings, the shoe 10 is substantially similar to that previously described, the same having its perimeter provided with a downturned flange 11, the flange, however, in this instance having neither toe nor heel projections or calks. This construction of shoe is particularly adaptable for light weight animals, such as colts, saddle horses, or racing steeds.

From the foregoing description, when taken in connection with the drawings, it

is manifest that I have produced an extremely simple construction of shoes for animals, one which may be cheaply manufactured and marketed, one which, while embodying a greater strength than that of the ordinary shoe, is materially lighter than such shoe, and one in which the calks, when employed, are formed on the body of the shoe in the manufacture of the shoe. 45

If desired, the shoe, as illustrated in Fig. 5, may have at its toe portion, at its heel portion, or at both of such portions, calks which, however, will not project beyond the edges of the flange 11. 50

Having described the invention, I claim:

A horseshoe constructed from a strip of sheet metal, a continuous flange depending from the perimeter of the shoe and being integrally formed therewith, an arcuate toe extension formed on the flange and being of a height approximately equaling the width of the shoe at the toe portion, heel projections formed on the flange and having their outer ends bent laterally and inwardly, extensions formed on the projections and being bent inwardly against the end of the shoe and the projections respectively, said projections and extensions forming pockets, filler blocks designed to fill the pockets, and said toe portion being weightier than the heel extension, for the purpose specified. 60

In testimony whereof I affix my signature. 70

CALVIN L. LUALLEN.
